UNITED STATES PATENT OFFICE.

WILLIAM FRANK BROWNE, OF NEW YORK, N. Y.

PROCESS OF AND APPARATUS FOR GENERATING GAS.

SPECIFICATION forming part of Letters Patent No. 268,863, dated December 12, 1882.

Application filed June 30, 1881. (No model.)

To all whom it may concern:

Be it known that I, WM. FRANK BROWNE, of the city, county, and State of New York, have invented an Improved Process of and 5 Apparatus for Generating Gas; and I do hereby declare the following specification to be a full and clear description thereof, reference being had to the accompanying drawings, which are an essential feature of the hereinabove-described invention.

This invention relates to a new mode or process and the means for generating heating, illuminating, and other gases under low or high pressure.

15 My invention, so far as relates to apparatus, is illustrated in the accompanying drawings, in which—

Figure 1 represents a vertical sectional view of the generator and its connections. Fig. 2 20 represents a horizontal sectional view showing one of the generating coils or conduits with its induction and eduction pipes diametrically opposite each other. Fig. 3 represents a horizontal sectional view showing one of the generating coils or conduits with its induction and eduction pipes extending tangentially to the inner and outer turns of the coil and the eduction-pipe connected to the vapor or gas receiver.

25 The generating-coils *a* are mounted or supported in the shell or case *A* upon lugs or projections *v*, cast with or attached to a vertical bar, *v'*, or upon projections secured directly to the shell. The induction and eduction ends of 30 the coils pass through the shell at diametrically-opposite points, as shown in Fig. 2, or they project through the shell at the rear, as shown in Fig. 3. The induction end *a* enters at *a'''* and passes to near the center of the casing, from which it is coiled outward, and finally projects through the shell, and is connected by a right and left coupling, *a'*, and nipple *a''* to the stand-pipe or receiver *H*. The mixed oil and water from which gas is generated is forced 35 through the pipe *f* by means of pump *K*, which connects with the uppermost coil *a*, or directly with one or more other coils, if desired. The mixed liquid circulates through the upper coil and through upper return-bend, *t*, into the second coil, and thence through the return-bend 40 *q* into the third coil, and thus on continuously

through the series until finally discharged into receiver *H* in the form of vapor or gas. The last coils, instead of discharging directly into the receiver *H*, may connect with a manifold, 55 fitting, *p*, which connects by pipes *u u* with the receiver *H*. From the receiver *H* the gas or vapor is conducted by pipe *e*, controlled by valve 2, into the dome *B*, from which it is conducted to the superheater *b*, to the forcing device, and, if desired, to other places of use. The mixed gas or vapor is conducted by pipe 60 *e*, controlled by valve 4, into the superheating-coil *b* at the base of the furnace, where it is completely decomposed and converted into a 65 fixed gas, which is discharged through valve 5 and conducted to any place desired. A portion of the gas or vapor is conducted by pipe *d*, controlled by valve 1, to a forcing-pump, *K*, for feeding the mixed hydrocarbon liquid and 70 water to the generator. A portion may also be conducted by pipe *d'*, controlled by valve 8, to an engine. The exhaust gas or vapor may be conducted from the force-pump or engine, or both, through the pipe *c'*, controlled by 75 valve 7, into the superheater *b* for conversion into fixed gas. Any condensed matter forming in pipe *c* is drawn off through the drip-pipe *c''*, controlled by valve 6. The pipe *i* serves as a drip-pipe and as a support to the 80 stand-pipe or receiver *H*. The condensed matter which may form in receiver *H* is conducted from pipe *i* by pipe *h*, controlled by valve 9, into and through trap *g*. The usual grate-bars, *k*, are placed near the base of the furnace, and 85 below these the ash-pit, *l*, is provided. A door, *o*, is provided above the grate-bars. The coils *b* connect at each side of the door with a suitable header or fitting, *n*. The usual uptake, *C*, extends from the top of the furnace. The 90 shell *A* of the furnace is made of two sections joined by bolts and flanges, as shown at *S S'*, Figs. 2 and 3. The main part of the shell may be joined to the fire-box by the flange *j*. An inner segmental shell, *B'*, may be provided, 95 conforming to the outer turn of coils, to diminish the flue-space between the shell and the coils. The space between the outer shell, *A*, and the inner segmental shell, *B'*, is filled with a packing of asbestos or other non-conducting 100 substance.

The specific construction and arrangement

of the generating-conduits or coiled sections and their adjuncts, together with its various applications, are not claimed in this application, as they form subject-matter for specific 5 claims which I reserve to myself the right to claim in subsequent applications.

What I claim, and desire to secure by Letters Patent, is—

1. The process of manufacturing gas or vapor, which consists in forcing a mixture of liquid hydrocarbon and water through a heated coil or conduit and discharging the gas or vapor produced into a suitable receiver.

2. The process of manufacturing gas or vapor, which consists in forcing a mixture of liquid hydrocarbon and water under high pressure through a heated coil or conduit and discharging the resulting gas or vapor into a receiver.

3. The process of manufacturing a fixed gas 20 for illuminating or heating purposes, which consists in forcing a mixture of carbonaceous matter and water under pressure through a heated conduit and discharging the resulting gas or vapor into a receiver, and then decomposing the mixed gas or vapor in a superheater and forming a fixed gas.

4. The combination of the generating-coils, the receiver, the decomposing and fixing coils, and a forcing device for oil and water for the 25 30 production of a fixed gas.

WM. FRANK BROWNE.
